United States Patent [19]

Yamamoto et al.

[11] Patent Number: Des. 274,891

[45] Date of Patent: ** Jul. 31, 1984

[54] MICROMETER

[75] Inventors: Takeshi Yamamoto; Hiroshi Yamashiro; Tokuzo Nakaoki, all of Kawasaki, Japan

[73] Assignee: Mitutoyo Mfg. Co., Ltd., Tokyo, Japan

[**] Term: 14 Years

[21] Appl. No.: 349,195

[22] Filed: Feb. 17, 1982

[30] Foreign Application Priority Data

Sep. 4, 1981 [JP] Japan 56-39105

[57] CLAIM

The ornamental design for the micrometer, as shown and described.

DESCRIPTION

FIG. 1 is a front and top-right perspective view of a micrometer showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a cross-sectional view as taken from line A—A of FIG. 4; and

FIG. 9 is a cross-sectional view as taken from line B—B of FIG. 4.

FIG. 1

FIG. 2

FIG. 3

FIG. 4

FIG. 5

FIG. 6

FIG. 7

FIG. 8

FIG. 9
